STRIKER FOR DOORLOCKS

Filed Dec. 24, 1930

Alexander S. Batz INVENTOR.

BY
Norman Frickstein
ATTORNEY

UNITED STATES PATENT OFFICE

ALEXANDER S. KATZ, OF BROOKLYN, NEW YORK

STRIKER FOR DOORLOCKS

Application filed December 24, 1930. Serial No. 504,572.

This invention relates to strikers or keepers for door locks and is particularly directed to a highly improved adjustable keeper for a latch lock.

Among the objects of this invention is to provide a strong, compact and rugged keeper of the character described, which shall comprise relatively few and simple parts, easy to adjust, be comparatively inexpensive to manufacture, positive in action, and yet practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a rear elevational view of a keeper embodying the invention;

Fig. 2 is a cross-sectional view taken on line 2—2 of Fig. 1;

Fig. 3 is a rear elevational view of a modified construction;

Fig. 4 is a cross-sectional view taken on line 4—4 of Fig. 3; and

Fig. 5 is a view similar to Fig. 4 but showing the strike member in a differently adjusted position.

Referring now in detail to the drawing, 10 designates a keeper embodying the invention comprising a member 11 provided with an end plate 12 having outwardly extending ears 13 each formed with an opening 14 for receiving any suitable fastening means, whereby said member 11 may be attached to a door jamb 15. Extending from said end plate 12, at right angles thereto, is a rear wall 16, side walls 17 and 18 and a front wall 19, the latter wall terminating as at 20 short of the walls 16, 17 and 18, and forming a tubular opening 21. Movable received within said opening 21 is the shank 22 of the strike member 23. A plurality of washers or shims 24

may be interposed between the end 25 of the shank 22 and the end wall 12. Said end wall 12 is formed with a countersunk opening 26 slidably receiving a screw 27, the shims 24 likewise being formed with registering openings 28 for slidably receiving said screw. The shank 22 is formed with a screw threaded opening 29 for receiving the screw threaded end of the screw 27. It will now be obvious that upon tightening the screw, the strike member will be clamped against the shims to produce a rigid construction.

Any suitable number of shims may be interposed between the end wall 12 and the strike member, whereby the position of the head 30 of the strike member with respect to the door jamb may be adjusted. Said head 30 is formed with an inclined inner surface 31 adapted to be engaged by the edge 31a of the lock bolt, said head extending beyond the end portion 20 of said front wall 19. A compression spring 35 serves to press the bolt toward the keeper whereby the edge 31a of the bolt tends to ride on the inclined surface 31 for tightly clamping the door or like portion 75 to which the lock may be fixed. A screw 32 screwed within a screw threaded opening 33 formed in the wall 19 serves to clamp the strike member 22 against the rear wall 16, thus adding to the rigidity of the construction.

To adjust the position of the strike member it is merely necessary to loosen the screw 31, unscrew the screw 27, remove some or all of the shims 24 or add shims, and then again screw the screw 27 within the screw threaded opening of the shank.

In accordance with the modified construction in Figs. 3, 4 and 5, there is provided a member 40, having ears 41, provided with openings to receive fastening means for securing said member 40 to the door jamb. Said member 40 further comprises a rear wall 42, side walls 43 and 44 and a parallel wall 45 interconnecting said side walls 43, 44. The rear wall 42 is formed on the inner surface thereof with a cylindrical bore or bearing opening 46 for the purpose hereinafter appearing.

Rotatably mounted on said rear wall 42

is a member 47, having a cylindrical extension 48 received within said bearing opening 46 and a substantially square-shaped portion 49 adapted to contact the inner surface 50 of said rear wall 42. The member 47 is provided with a transverse cylindrical opening 52 coaxial with the cylindrical portion 48. The axis of said opening 52 is preferably eccentric with respect to the edges of said square-shaped portion 49, that is, the perpendicular distances from the axis of said opening 52 to the edge of said square-shaped portion 49 are unequal.

Received between the side walls 43, 44 of member 40 is a strike member 55 having a head 56 extending away from said wall 42. Said member 55 is formed with a transverse slot 57 on the rear surface thereof for receiving the portion 49 of member 47.

It will be noted that the distance between the parallel edges 58 and 59 of said slot is equal to the length of an edge of the portion 49. The length of the slot, however, is at least equal to the length of one of the edges of said portion 49 plus the difference between the shortest perpendicular distance from the axis of the opening 52 to one of the edges of said portion 49 and the longest perpendicular distance between said axis and an edge of said portion 49. This construction will permit the member 47 to be moved to four positions at right angles to one another and the square-shaped portion 49 will be snugly received within the slot 57. The member 55 is provided with a longitudinal countersunk slot 60 and extended through said slot is a screw 61 slidably extending within said opening 52 and having a screw threaded end portion 62 which may be screwed into a screw threaded opening 63 formed in said wall 42 on the inner surface thereof and disposed coaxially with respect to the cylindrical bearing opening 46.

It will now be understood that the member 47 may be moved to four positions for adjusting the position of the strike member 55 with respect to the door jamb, and in each adjusted position the screw 61 may be tightened to fix the strike member 55 to the member 40.

Thus in the position shown in Figs. 3 and 4, the strike member 55 is in the outermost position thereof, since the perpendicular distance from the axis of screw 61 to the edge of the square portion 49 which contacts the edge 58 is greater than the perpendicular distance from said axis to any of the other three edge portions of square-shaped portion 49. For adjusting the keeper from the position shown in Fig. 3 to the position shown in Fig. 5, the screw 61 is unloosened and the member 48 rotated 90° in a counterclockwise direction (looking at Fig. 3). The member 55 is then replaced and the screw 61 again screwed for clamping the parts together. This adjustment will bring the member 55 inwardly to-

ward the door jamb. The remaining two adjustments may be made by rotating the member 48 to the proper position, and clamping the parts together by means of the screw 61.

The head 56 may likewise be formed with an inner inclined surface 56a adapted to be engaged by an outer edge of the projected bolt for causing a tight clamping or closing of the door on which the bolt is mounted.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A lock keeper comprising a member having a portion adapted to be attached to a door jamb, a tubular portion extending therefrom, a strike member having a shank extending within said tubular portion, said first portion being formed with an opening, a screw extending through said opening and screwed to said shank, and one or more shims interposed between said first portion and the said shank.

2. A lock keeper comprising a plate portion adapted to be attached to a door jamb, said portion being formed with an opening, a screw member slidably extending through said opening, a strike member having a shank formed with a screw threaded opening receiving the screw threaded portion of said screw.

3. A lock keeper comprising a plate portion adapted to be attached to a door jamb, said portion being formed with an opening, a screw member slidably extending through said opening, a strike member having a shank formed with a screw threaded opening receiving the screw threaded portion of said screw, and one or more removable washers interposed between said shank and said plate portion.

4. A lock keeper comprising plate portion adapted to be attached to a door jamb, said portion being formed with an opening, a screw member slidably extending through said opening, a strike member having a shank formed with a screw threaded opening receiving the screw threaded portion of said screw, and one or more removable washers interposed between said shank and said plate portion, each of said washers being formed with an opening slidably receiving said screw therethrough.

5. A lock keeper comprising a member

- having a plate portion adapted to be attached to a door jamb, a flat rear wall extending perpendicularly to said portion, a pair of flat parallel side walls extending from said rear wall, a front wall spaced from and parallel to said rear wall, interconnecting said side walls, said front wall terminating short of the ends of said side walls, a strike member slidably contacting said side walls and rear wall, means for fixing said strike member to said first member only in a plurality of predetermined adjusted positions, and means for predetermining said positions of said strike member.
6. A lock keeper comprising a member having a plate portion adapted to be attached to a door jamb, a rear wall extending perpendicularly to said portion, a pair of parallel side walls extending from said rear wall, a front wall spaced from and parallel to said rear wall, interconnecting said side walls, said front wall terminating short of the ends of said side walls, and a strike member having a shank formed with a smooth surface slidably received between said front, rear and side walls and a head disposed between said side walls and projecting away from said rear wall and beyond said front wall.
7. A lock keeper comprising a member having a plate portion adapted to be attached to a door jamb, a rear wall extending perpendicularly to said portion, a pair of parallel side walls extending from said rear wall, a front wall spaced from and parallel to said rear wall, interconnecting said side walls, said front wall terminating short of the ends of said side walls, and a strike member having a shank received between said front, rear and side walls and a head projecting away from said rear wall, said plate portion being formed with an opening, said shank being formed with a screw threaded opening coaxial with said first mentioned opening and a screw extending through said first opening and screwed into said screw threaded opening.
8. A lock keeper comprising a member having a plate portion adapted to be attached to a door jamb, a rear wall extending perpendicularly to said portion, a pair of parallel side walls extending from said rear wall, a wall spaced from and parallel to said rear wall interconnecting said side walls, and a strike member having a shank received between said front, rear and side walls and a head projecting away from said rear wall, said plate portion being formed with an opening, said shank being formed with a screw threaded opening coaxial with said first mentioned opening and a screw extending through said first opening, screwed to said screw threaded opening, and a plurality of washers interposed between said plate portion and the end surface of said shank.
9. A lock keeper comprising a member having a plate portion adapted to be attached to a door jamb, a rear wall extending perpendicularly to said portion, a pair of parallel side walls extending from said rear wall, a wall spaced from and parallel to said rear wall interconnecting said side walls, and a strike member having a shank received between said front, rear and side walls and a head projecting away from said rear wall, said plate portions being formed with an opening, said shank being formed with a screw threaded opening coaxial with said first mentioned opening, a screw extending through said first opening and screwed to said screw threaded opening, and a plurality of washers, interposed between said plate portion and the end surface of said shank, said washers each being provided with an opening receiving said screw.
10. A keeper comprising a member adapted for attachment to a door jamb and having a circular opening, a second member having a circular portion on said second member rotatably received within said opening, and a second portion having a pair of parallel edges, and a strike member having a groove formed with parallel edges adapted to receive said second portion.
11. A keeper comprising a member adapted for attachment to a door jamb, a second member rotatably mounted on said first member and having a portion formed with a pair of parallel edges, and a strike member having a groove adapted to receive said portion, the perpendicular distance between the axis of rotation of said second member and said parallel edges being unequal.
12. A keeper comprising a member adapted for attachment to a door jamb and having a circular opening, a second member having a circular portion rotatably received within said opening, and a second portion on said second member, having a pair of parallel edges, contacting the surface of said first member adjacent said opening, and a strike member having a groove formed with parallel edges adapted to receive said portion, said strike member having a slot therein and a screw member extending through said slot, said second member being provided with an opening coaxial with said circular portion, said first member being provided with a screw threaded opening registering with said opening in said second member, said screw threaded member slidably extending through the opening in said second member and being adapted to be screwed to said screw threaded opening.
13. A lock keeper comprising a member having a cylindrical opening, a second member having a cylindrical portion rotatably received within said cylindrical opening and a square portion, the axis of said cylindrical portion being eccentric with respect to the edge portions of said square portion, and a

strike member having a groove receiving said square portion therein with a pair of parallel edge portions of said square portion contacting the parallel walls of said groove.

14. A lock keeper comprising a member having a cylindrical opening, a second member having a cylindrical portion rotatably received within said cylindrical opening, and a square portion, the axis of said cylindrical portion, being eccentric with respect to the edges of said square portion and a strike member having a groove receiving said square portion therein with a pair of parallel edge portions of said square portion contacting the parallel walls of said groove, said strike member being formed with a longitudinal slot, said second member being formed with an opening coaxial with said cylindrical portion and registering with said slot, said first member being formed with a screw threaded portion coaxial with said opening in said second member and a screw slidably extending through said slot and opening in said second member and screwed to the screw threaded opening of said first member.

15. A lock keeper comprising a member having a plate portion adapted to be attached to a door jamb, an integral straight wall extending perpendicularly to said portion, a pair of straight parallel side walls integrally formed with and extending from said rear wall, a front wall spaced from and parallel to said rear wall and interconnecting said side walls, said front wall terminating short of the ends of said side walls, a strike member having smooth surfaces slidably contacting said side walls and rear wall, means for fixing said strike member to said first member only in a plurality of predetermined adjusted positions, and means for predetermining the said positions of said strike member, said strike member having a head disposed between said side walls and projecting away from said rear wall and beyond said front wall.

16. A lock keeper comprising a member having a plate portion adapted to be attached to a door jamb, an integral straight wall extending perpendicularly to said portion, a pair of straight parallel side walls integrally formed with and extending from said rear wall, a front wall spaced from and parallel to said rear wall and interconnecting said side walls, said front wall terminating short of the ends of said side walls, a strike member slidably received between said side walls and front and rear walls, said strike member having a head disposed between said side walls and projecting away from said rear wall, and beyond said front wall, a member interposed between said strike member and said first member and having a surface perpendicular to said rear, front and side walls, and contacting a portion of said strike member and

means for attaching said strike member and interposed member to said first member.

17. A lock keeper comprising a member having a plate portion adapted to be attached to a door jamb, an integral straight wall extending perpendicularly to said portion, a pair of straight parallel side walls integrally formed with and extending from said rear wall, a front wall spaced from and parallel to said rear wall and interconnecting said side walls, said front wall terminating short of the ends of said side walls, a strike member slidably received between said side walls and front and rear walls, said strike member having a head disposed between said side walls and projecting away from said rear wall and beyond said front wall, and a member having a surface perpendicular to said rear, front and side walls, and contacting a portion of said strike member, said last named member having an opening therethrough, and a screw extending through said opening and engaging said first member and strike member.

18. A lock keeper comprising a member adapted to be attached to a door jamb having a rear wall and side walls extending from said rear wall, a strike member received between said side walls of said first member, and a member interposed between and contacting said strike member and first member and provided with a through opening, and a screw extending through said opening engaging said first member and strike member.

19. A lock keeper comprising a member adapted to be attached to a door jamb having a rear wall and side walls extending from said rear wall, a strike member received between said side walls of said first member, and a member having a surface contacting the surface of said strike member, said last named member being provided with a through opening and a screw extending through said opening, and having portions engaging said first member and strike member.

20. A lock keeper comprising a member adapted to be attached to a door jamb, a strike member, and a member interposed between said strike member and first member, said last member having an opening therethrough, one of said first two members being formed with a through opening, and the other of said first two members being formed with a screw threaded opening, and a screw extending through said last named through opening, and through the opening in said third member and engaging the threads of said screw threaded opening.

In testimony whereof I affix my signature.

ALEXANDER S. KATZ.
